UNITED STATES PATENT OFFICE.

ADOLF KRAUSS, OF CANNSTATT, GERMANY, ASSIGNOR TO THE FIRM OF ROBERT BOSCH, OF STUTTGART, GERMANY, A CORPORATION OF GERMANY.

DESIGN FOR A CAM-RING FOR MECHANICAL INTERRUPTERS IN ELECTRICAL IGNITION SYSTEMS.

46,503.

Specification for Design.

Patented Oct. 6, 1914.

Application filed June 5, 1914. Serial No. 843,313. Term of patent 7 years.

To all whom it may concern:

Be it known that I, ADOLF KRAUSS, a subject of the Emperor of Germany, residing at 8 Bryestrasse, Cannstatt, Germany, have invented a new, original, and ornamental Design for a Cam-Ring for Mechanical Interrupters in Electrical Ignition Systems, of which the following is a specification, reference being had to the accompanying drawings, forming part thereof.

The figure is a perspective view of a cam ring for mechanical interrupters, showing my new design.

I claim—

The ornamental design for a cam ring for mechanical interrupters in electrical ignition systems, as shown.

In testimony whereof, I affix my signature, in presence of two witnesses.

ADOLF KRAUSS.

Witnesses:

PAUL WOLFART,
REINHOLD EHVERT.
